United States Patent Office

Des. 193,369
Patented Aug. 7, 1962

193,369

AIRPLANE

Howell L. Walker and Raymond A. Young, Los Angeles,
Calif., assignors to Douglas Aircraft Company, Inc.,
Santa Monica, Calif.

Filed Mar. 29, 1961, Ser. No. 64,598

Term of patent 14 years

(Cl. D71—1)

Fig. 1

Fig. 2

FIGURE 1 is a perspective view taken from a forward position and from the top and one side, of an airplane embodying our new design;

FIGURE 2 is a front elevational view of the airplane;

FIGURE 3 is a bottom plan view of the same;

FIGURE 4 is a side elevational view of the airplane, the opposite side having no door but otherwise being substantially the same in appearance.

The exhausts at the sides of the fuselage, as shown in FIGURES 1 and 4, are provided with a series of vanes.

We claim:

The ornamental design for an airplane, substantially as shown and described.
